N° 1,729. Application II.⁵

E. F. May.

Design for a Carpet Pattern.

Patented March 3, 1863.

Watson } J. S. Chapman E. F. May
Watson } Robt. R. Campbell. Dec. 1729

Elemin J. Ney, of Lowell, Mass.

Assignor to.

The Lowell Manufacturing Company.

Letter Patent No. 7729, dated March 3, 1863.

The schedule referred to in these Letters Patent and making part of the same.

To all whom it may concern:

Be it known that I, Elemin J. Ney, of Lowell, in the County of Middlesex, and State of Massachusetts, now temporarily residing in New York, have originated and designed a new Pattern for carpets or other fabrics, of which the following is a full, clear and exact description, reference being had to the accompanying drawings making part of this specification.

A, at the top of the drawing, is one half of a set figure, having sixteen arms or projections; in the centre of this figure is a small octagonal frame enclosing a small rosette.

The block of key-work B, supports fig. A, and is surrounded by the frame C. A band of small set figures D, surrounds the frame C. E, is one half of an oblong figure composed of combinations of Persian figures, resting on the ground, which is enclosed by the outline frame F. The band G, which is similar to band D, surrounds the frame F. 4, and 5, at the sides when matched form an oblong set figure which rests on a cross shaped ground surrounded by the broad frame H. 6.

In the four corners are fourths of figures, composed of a number of small blocks enclosed by a narrow diamond shaped frame.

The spaces between the frame H, G, and the bands D, and F, are occupied by combinations of lines and blocks arranged as shown in the drawing.

The colors employed for the different portions of the design may be varied to suit the taste and wish of the manufacturer.

~ Claim. ~

What I claim as my invention, and desire to secure by letters patent, is the design or pattern, for carpets, or other fabrics, herein set forth.

Witnesses.
